UNITED STATES PATENT OFFICE.

FLOYD JOHNSTON, OF LANESBORO, IOWA, ASSIGNOR OF ONE-THIRD TO WALTER S. PIATT, OF LANESBORO, IOWA, AND ONE-THIRD TO CLARA WILSON, OF LIDDERDALE, IOWA.

STARTING DEVICE FOR INTERNAL-COMBUSTION ENGINES.

1,184,961.

Specification of Letters Patent. Patented May 30, 1916.

Application filed August 14, 1915. Serial No. 45,595.

To all whom it may concern:

Be it known that I, FLOYD JOHNSTON, a citizen of the United States of America, and a resident of Lanesboro, Carroll county, 5 Iowa, have invented certain new and useful Improvements in Starting Devices for Internal-Combustion Engines, of which the following is a specification.

My invention relates to improvements in 10 starting devices for motors, and the object of my improvement is to provide a simple and efficient mechanically actuated device containing yieldable resilient elements adapted to be placed in and releasably secured in a state of potential stress adapted 15 to crank the motor-shaft when released, by power derived from the action of the motor itself. This object I have accomplished by the means which are hereinafter described 20 and claimed and which are illustrated in the accompanying drawings, in which—

Figure 1 is a side elevation of my improved starting device, showing portions in 25 central longitudinal section. Fig. 2 is a front elevation of said device, showing it operatively connected to the crank-shaft of a motor. Fig. 3 is a cross section of said device, taken on the line *a*—*b* of said Fig. 1. Fig. 4 is a cross section, taken through the 30 roller-clutch on the line *c*—*d* in Fig. 1.

Similar numerals of reference denote corresponding parts throughout the several views.

1 is a shaft whose ends are fixedly mounted 35 in bearings in the frame composed of offset uprights 50 connected by integral horizontal cross beams 48 and 49. The cross beam 48 is secured to the top of the cylinder casing of the motor 3, the latter having the sprocket 40 wheel 4 secured on the forward end of its crank shaft 2. A sleeve 9 is rotatably non-slidably mounted on the left-hand part of the drum-hub 20 rotatable on the shaft 1 within said frame, and has a longitudinal 45 spline 10. 15 is a collar provided with an annular groove 12 and ratchet-clutch teeth 11, and is mounted slidably non-rotatably on said sleeve 9 to slide lengthwise over the spline 10. 8 is a mating clutch member for 50 the other member 11 mounted rotatably on said sleeve 9 and has integrally connected therewith, a cylindrical hollow housing 7 and a sprocket wheel 6. A sprocket chain 5 connects the sprocket wheels 4 and 6. 55 Within the housing 7 are the rollers 52

adapted to coact with opposite projections 51 on the drum-hub 20 to supply a roller-clutch between the housing and said sleeve.

14 is a vertical arm extending from a horizontal rod 18 and has at its upper end a fork 60 13 whose bifurcations are seated in the groove 12 of the clutch-body 15. A lever 44 is medially fulcrumed on a projection 45 from said frame 50, and has its lower end pivoted to the right hand end of the rod 18, 65 which latter is threaded at 46 to receive an adjusting nut 47.

16 is a pinion fixedly mounted on the right hand end of the sleeve 9 abutting upon the fixed fillet 20 on the shaft 1. A gear-wheel 70 17 is in mesh with said pinion and is mounted upon a short shaft 21 rotatable in bearings in a pair of spaced uprights 19 projected from the lower frame bar 49, the right hand end of said shaft extending to 75 the right of the right hand standard 19 and carrying a pinion 22.

24 is a hollow drum mounted on the hub 80 20 rotatable about the coaxial with the shaft 1 and having an internal gear 23 in its left hand end with which the pinion 22 is intermeshed. The right hand end of said drum is closed by means of a head 27 which has an exteriorly threaded sleeve 28 extending to the right as far as the right hand frame 85 bar 50 and rotatably mounted upon the shaft 1. Within said drum is a spaced pair of flat coiled springs 26 whose outer ends are secured to the inner wall of the drum and whose inner ends are secured to the hub 90 20 on said shaft 1. The numerals 29 and 30 denote like bodies of oblong form arranged vertically with their lower ends bifurcated to ride astride the lower frame bar 49. The upper part of the body 29 is 95 smoothly orificed to seat it about the threaded hub 28 of said drum, while the upper part of the other body 30 has an interiorly threaded orifice permitted to be seated upon and intermeshed with said threaded hub 28. 100 A downwardly curved arm 31 has its lower end pivotally connected to the upper end of the body 29 and a short link 32 is pivotally connected between the upper end of the body 30 and the middle of the curved part of said 105 arm 31. The upright part of the arm 31 has a pintle 37 received slidably within a longitudinal slot 36 in the left hand end of a bar 34 which extends to the right through an opening in a foot-board 42 and is pro- 110

vided at its right hand end with a foot pedal 41. A spring 43 is connected between the bar 34 and the foot-board 42. A short arm 38 is pivotally connected to the middle of the bar 34 to extend horizontally, and coiled springs 40 are connected between opposite sides of said arm and to different parts of the bar to exercise equal and opposite tensions upon the arm. Said arm lies within the path of movement of the free upper end of the lever 44.

Operation: Fig. 1 shows my starting device with its elements in operative positions for cranking the motor shaft 2, with the spiral springs 26 under tension, and with my releasable locking means holding the drum 24 in locked position. The releasable locking means comprises the curved arm 31 and link 32, connected pivotally to each other and to the bodies 29 and 30. In the positions of these parts shown in said Fig. 1, the pintle 33 has been moved downwardly beyond the dead center relative to the pivotal connections between said bodies and said arm and link, which locks them together to hold the body 29 in braking frictional contact with the head 27 of the drum 24, preventing rotation of the latter when the springs 26 are wound up. To start the motor 3, the pedal 41 and bar 34 are pushed to the left. This rocks the arm 31 upwardly until the pintle 33 passes its dead center, and the body 29 is shifted to the right enough to release the drum 24. The springs 26 then react to rotate the drum, and sprocket-wheel 6, through the inclosed roller-clutch in the housing 7, whereby the chain 5 rotates the motor shaft 2. In rotating, the threaded sleeve 28 carries the body 30 to the left a certain distance relative to the adjustable stop-nut 47 on the threaded end 46 of said rod 18. Simultaneously, the arm 31, while swinging upwardly, after its release, permits the bar 34 to be shifted to the right under the impulsion of the stretched spring 43. The arm 38 on said bar rocks the upper end of the lever 44 to the right until the right-hand spring 40 yields enough to let said arm swing and slip under the lever-end 50 to a position to the right thereof. The lower end of the lever 44 is thus rocked to the left with the rod 18, forked arm 14, and clutch-member 15, until the teeth thereof mate with the teeth of the other clutch-member 8. Since the motor is in operation, and the member 8 running idly, when the members 8 and 15 are mated, the roller-clutch engages appropriately, whereby the sleeve 9, and also said gearing and said drum are rotated 60 reversely, to wind up the springs 26. The threaded sleeve 28 now returns the body 30 to the right to simultaneously move to the right, the adjustable stop-nut 47 with the rod 18, which latter causes the clutch-members 8 and 15 to disengage. In moving to

the right, the body 30 rocks down the arm 31, to push the body into locking contact with said drum, the pintle 33 again passing beyond the dead center. The parts are thus placed in their initial positions automatically.

To initially set the device in an operative condition, the motor-shaft may be rotated by a hand-crank, after the clutch-member 15 has been engaged with the member 8 by 75 manually moving the bar 34 to the right. Manual rotation of the motor-shaft then causes a winding up of the spring 26, with the concurrent locking of the drum as above described. When the pedal 41 is pushed to 80 the left to release the drum, the swing-arm 38 passes under and to the left of the lever 44, because of the yielding of the left-hand spring 40. After this initial setting of the device, it is afterward automatically replaced in an operative condition, after each 85 actuation in starting the motor, by the driving action of the motor itself as described. Back firing does not affect the device, because of the employment of ratchet-teeth on 90 the clutch-members 8 and 15.

Various changes may be made in the form, arrangement, dimensions or relations of the elements of my device, without departing from the protection of or the principles of 95 my invention.

Having described my invention, what I claim as new, and desire to secure by Letters Patent, is:

1. A starting device for a motor-shaft, 100 comprising a rotary clutch-member operatively connected to said motor-shaft, a rotary body on which said clutch-member is disengageably mounted, a mating clutch-member slidably non-rotatably mounted on 105 said rotary body, a rotatable drum, driving connections between said rotary body and drum, a supporting body for said rotary body, a main-spring connected between said drum and said rotary body, disengageable 110 means for locking said drum while said spring is under tension, means for disengaging said locking-means, and other means connected thereto and to the second-mentioned clutch-member adapted to coact in 115 disengaging the clutch-members automatically when said spring is released.

2. A starting device for a motor, comprising in combination with a motor-shaft, a fixed shaft, a drum-hub rotatable thereon, a sleeve rotatable on said drum-hub, sprocket-wheels on said sleeve and motor-shaft, a sprocket-chain connecting said sprocket-wheels, a housing integral with the sprocket-wheel on said sleeve, a roller-clutch mounted between said housing and said drum-hub, said housing having an integral 125 clutch-member, another sleeve rotatable on said drum-hub, a mating clutch-member slidably non-rotatably mounted on said 130

sleeve and adapted to disengageably engage the first-mentioned clutch-member, a hollow drum fixed on said hub and rotatable on said fixed shaft and provided with an internal-
5 gear, a pinion fixed on said second-men-
tioned sleeve, a short shaft having a gear-
wheel in mesh with said pinion and also hav-
ing a pinion in mesh with said internal-gear,
a spiral spring in said drum with its outer
10 end connected to the drum and its inner end
connected to the said fixed shaft, said drum
having an exteriorly-threaded sleeve hub ex-
tension fixed in one end and rotatably
mounted on said fixed shaft, a body slidably
15 mounted on said sleeve-hub, another body
having an interiorly threaded orifice mount-

ed upon and in mesh with said sleeve-hub, a
downwardly-bent arm pivoted to the first
body, a link pivotally connected between the
bent part of said arm and the second body, 20
means for rocking said arm, and other means
operatively connected between said means
and the second - mentioned clutch - member
adapted to coact therewith in automatically
disengaging said clutch-members when said 25
springs are wound up by the motor-shaft.

Signed at Waterloo, Iowa, this 28th day of
July, 1915.

FLOYD JOHNSTON.
